UNITED STATES PATENT OFFICE.

EARL G. HANEY, OF CHICAGO, ILLINOIS.

FOLDING BENCH AND TABLE.

Application filed September 2, 1924. Serial No. 735,246.

To all whom it may concern:

Be it known that I, EARL G. HANEY, a citizen of the United States, residing at Chicago, Cook County, Illinois, have invented certain new and useful Improvements in Folding Benches and Tables, of which the following is a specification, reference being had to the accompanying drawings, forming part hereof.

These improvements relate to benches and tables formed to collapse or fold into a relatively small space for convenience in storage and transportation. The principal objects of the present improvements are to provide a device of the character described according to which the two sections may be folded together or opened without releasing catches or locking elements ordinarily difficult for one unacquainted with a given device to find and operate; to provide a structure of substantially few parts easily to be made and assembled, which is unusually strong, and which will not readily get out of order.

In the drawings, Figure 1 shows my improved table or bench in side view as extended for use, one half of the device being sectionally shown; Fig. 2 shows a bottom view of the same; Fig. 3 shows the structure partially collapsed, and with one of the body sections in longitudinal medial vertical section as in Fig. 1; and Fig. 4 is a perspective of the device as it appears closed.

I provide two body sections A and B which are preferably provided with marginal flanges 10, 11, 12 and 13 respectively, the opposite ones of which abut each other as shown in Fig. 4 when the device is closed and provide space inside for the legs and the system of links and levers employed.

While I have shown a pair of the operative mechanisms associated with each body section A and B, one of these mechanisms associated with each section A and B will suffice, in which instance the operative links and levers would be positioned substantially at the longitudinal middle on the normally under side of the sections respectively.

Since the operative parts are the same on

each side of the hinge 15 connecting the sections A and B it will be sufficient to describe only one of these mechanisms in detail. Like parts are given like reference numerals.

Referring for convenience to the right-hand portion of Fig. 3, it will be noted that there is an inner leg 16 and an outer leg 17 hinged to the body section B to fold inward. Also that a fulcrum bar 18 is hingedly mounted at one end to the section B at 19 to fold inward also. At 20 this fulcrum bar 18 is pivotally mounted to a lever 21 substantially midway between its ends, while a link 22 pivoted at 23 to the lever 21 and at 24 to the leg 16 makes a push-and-pull connection between the leg 16 and the lever 21. A similar link 25 pivoted at 26 to the other end of the lever 21 connects at 27 to the outer leg 17. A slotted guide 28 is pivotally mounted at 29 upon the section B and a headed pin 30 secured upon the fulcrum bar 18 is adapted to slide in the slotted guideway of the member 28. A coiled spring 31 is connected to the bar 18 and to the section 29 and is adapted to draw the bar 18 in one direction until the pin 30 comes to the end of the slot in the member 28, the member 28 serving to limit the movement of the fulcrum bar 18 in the direction of pull by the spring.

Between the two inner legs 16 is a flexible element 32, suitably a chain section, which, as shown by Fig. 1, is of such length that it is taut when the legs 16 are directed normally outward, or substantially at right angles to the body members respectively when the device is fully opened.

Assuming the structure to be in open position, as in Fig. 1, it will be observed that both ends of the sections A and B are supported by legs and that there is thus provided a very stable device. When in open condition it may be moved about freely, for until the folding operation is begun the legs are maintained in their proper relative positions by the systems of links and levers shown and described, and the folding operation can not take place as long as the device normally stands upon its legs.

From Fig. 3 it will be noted that when the folding operation is begun the inner legs 16 come together and push against each other, and this pushing against each other is continued until the sections A and B come together. The legs 16, being bound to fold against the sections A and B respectively when those sections are folded upon each other, provide a push motion which is communicated through the links 22 to the lever 21, rocking that lever on its fulcrum 20, thereby drawing upon the links 25 and pulling inward the outer leg 17. This operation continues until the lever 21 becomes substantially in line with the fulcrum bar 18, at which time the continued push upon the link 22 causes the pin 30 to slide in the slot of the guide member 28, and the continued movement causes the fulcrum bar 18 to swing toward the body section until the fulcrum bar 18 and the guide member 28 have folded down substantially parallel to each other, at which time also the links 22 and 25 and the lever 21 have folded down, the sections A and B being at that time face to face.

On opening the sections A and B out of their relative positions shown in Fig. 4 all of the other movable parts remain in their folded position until the flexible member 32 becomes taut, at which time the sections are free to open further but the inner legs 16 are held against separation beyond the normal amount shown in Fig. 1. During the preliminary part of the opening operation the spring 31 draws the fulcrum bar 18 outward and the pin 30 comes to the end of the slot in the guide member 28, and thereupon the fulcrum 20 becomes effective and the ensuing pull upon the link 22 is converted into a push upon the link 25 having the effect of swinging the leg 17 outward.

The device is remarkably easy to operate since all of the movable parts automatically take their desired relative positions respectively by simply moving the body sections toward and away from each other.

I contemplate as being included in the present invention such changes, modifications and departures from what is herein specifically illustrated and described as fall within the scope of the appended claims.

I claim:

1. In a folding bench or table, the combination of two body sections hinged together to fold one upon the other, each section having an outer leg and an inner leg hinged thereto to fold toward each other and substantially against the body section to which hinged, a flexible element connecting the two inner legs and limiting their movement in one direction to a position in which the inner legs extend substantially at right angles to the body sections respectively when the device is in fully-opened

position, said inner legs being arranged to push against each other when the body sections are folded one upon the other, and means dependent upon the movement of the inner legs relative to the body members respectively for causing the outer legs to fold inward when the body sections are folded and for forcing the outer legs outward when the body sections are swung apart. 70

2. In a folding bench or table, the combination of two body sections hinged together to fold one upon the other, each section having an outer leg and an inner leg hinged thereto to fold toward each other and substantially against the body section to which hinged, a flexible element connecting the two inner legs and limiting their movement in one direction to a position in which the inner legs extend substantially at right angles to the body sections respectively when the device is in fully-opened position, said inner legs being arranged to push against each other when the body sections are folded one upon the other, and a system of links and levers between the inner and outer legs respectively for causing the outer legs to fold inward when the body sections are folded and to force the outer legs outward when the body sections are swung apart. 80 85 90 95

3. In a folding bench or table, the combination of two body sections hinged together to fold one upon the other, each section having an outer leg and an inner leg hinged thereto to fold toward each other and substantially against the body section to which hinged, a flexible element connecting the two inner legs and limiting their movement in one direction to a position in which the inner legs extend substantially at right angles to the body sections respectively when the device is in fully-opened position, said inner legs being arranged to push against each other when the body sections are folded one upon the other, and a system of links and levers between the inner and outer legs respectively for causing the outer legs to fold inward when the body sections are folded and to force the outer legs outward when the body sections are swung apart. 100 105 110

4. In a folding bench or table, the combination of two body sections hinged together to fold one upon the other in substantially parallel relation, each section 115 120 125

130

having an outer leg hinged thereto to fold substantially against the body section to which hinged, each section having also an inner leg, the inner legs being closely adjacent to each other, said sections being free to fold together when the legs are off of the floor, and being held against such folding by the resting of the device with its legs normally upon the floor and means depend-

ent upon the movement of the sections toward each other and the impingement of the inner legs upon each other for causing the legs to fold substantially parallel with the sections respectively when the sections are folded substantially parallel to each other. 10 15

EARL G. HANEY.
